UNITED STATES PATENT OFFICE.

BROOKS BUSH, OF ATLANTA, GEORGIA.

CAR-COUPING.

SPECIFICATION forming part of Letters Patent No. 394,909, dated December 18, 1888.

Application filed August 24, 1888. Serial No. 283,679. (No model.)

To all whom it may concern:

Be it known that I, BROOKS BUSH, a citizen of the United States, residing at Atlanta, in the county of Fulton and State of Georgia, 5 have invented a new and useful Car-Coupling; and I do hereby declare the following to be a full, clear, and exact description of the invention, such as will enable others skilled in the art to which it appertains to make and use the 10 same, reference being had to the accompanying drawings, and to letters or figures of reference marked thereon, which form a part of this specification.

This invention relates to the class of car- 15 couplings in which an arrow-head bolt is used in place of the usual link, the object being to make it automatic and certain in its operation.

It consists of a draw-head containing a 20 latch and mechanism to operate it connected to the outer corners of the car, an arrow-head bolt, and means of coupling with an ordinary link, the particulars of which will be herein-after fully set forth and the parts thought 25 to be new pointed out in the claims.

In the accompanying drawings, Figure 1 is a cross-section on the line *x*, Fig. 2, showing the interior of the draw-head and most of the operative parts. Fig. 2 is a longitudinal ver- 30 tical section through the draw-head on the line *y*, Fig. 1, showing the details shown in that figure and the arrow-head bolt. Fig. 3 is a front view of the draw-head, not showing the arrow-head bolt, but showing the 35 opening into which it goes. Fig. 4 is a top view or plan of the draw-head, showing the arrow-head bolt and the sliding catch by which it is secured and the lever by which the sliding catch is operated. Fig. 5 is a per- 40 spective of the device and the means of attaching it, and the chains by which it is operated, to a car. Fig. 6 is a section on the line *z*, Fig. 3, further showing the construction of the sliding catch.

45 In the several figures, like reference-marks referring to corresponding parts in the several views, *A* is a draw-head of any approved construction, except that it must be adapted to contain the operative parts hereinafter 50 described—that is to say, the sliding catch *B*, the shafts *C*, the arrow-head bolt *D*, the

opening *E*, and pin *F*. The bolt *D* (shown in Figs. 2 and 5) has a flange, *d*, in the center, to prevent the bolt entering the draw-head beyond the required distance, and the arrow- 55 heads *d'* on the ends. This bolt, being in one draw-head, as shown in those figures, is caused to enter an approaching draw-head by the conical concavity in the front of the draw-head, as shown in Figs. 3 and 6 and by 60 the dotted lines in Fig. 2. From the bottom of this conical concavity is an opening in the interior of the draw-head, of a slightly greater size than the arrow-head on the bolt *D*, which hole passes not only through the front of the 65 draw-head, but also through the sliding catch *B*. The sliding catch *B* is recessed on its back side, as shown in Fig. 6, to make a face 70 level with that of the inner side of the draw-head for the shoulder of the bolt-head to bear 75 on. The top side of the hole through this sliding catch is beveled, as shown in Figs. 3 and 6 and by dotted lines in Fig. 2, and it is obvious that the arrow-head on entering will raise the catch and pass through, when the 75 sliding catch will fall, partly by gravity and partly by the force of the springs *G*, Figs. 1 and 2.

The two draw-heads working together should be alike in all respects, and, with the 80 arrow-head bolt in one of them, the operation just described is that of coupling them. To uncouple them, the operation consists in raising the catch *B*, which is done by the levers *H* and the key *J*. The shafts *C* are pivoted in 85 the draw-head, the preferable manner being by the blocks *K* and *L*, and have on their forward ends cranks *h*, on which are rollers *h'*, and in their middle portions the upwardly-projecting double cranks *H'*. These double 90 cranks cross each other, as shown in Figs. 1 and 2, and the key *J*, having bearings in the top and bottom of the draw-head, passes between them. It is obvious that the pressing apart of the upwardly-projecting cranks will 95 raise the cranks *h* and with them the sliding catch *B* and release the arrow-head bolt, and that the turning of the key *J* will accomplish this result. At the top of the shaft *j* of the key *J* is a lever, *M*, which should extend in 100 the direction of the face of the draw-head and be provided with an eye, *m*, as shown in

Figs. 1, 2, and 3. To the eye *m* are attached the chains *N*, that extend to a point at or near the side of the car, as shown in Fig. 5, and have a sufficient slackness to permit the lever 5 *M* to swing the required distance in either direction to turn the key and raise the sliding catch, as above described. To prevent the key turning farther than is necessary to raise the catch to the required height, the 10 abutting-pieces *P* project inwardly from the sides of the draw-head, against which the cranks *H'* abut.

To couple with the ordinary link, it is passed into the opening *E* at the top of the 15 draw-head and fastened by the pin *F*, the parts having proportions according to the strength of the metal from which the draw-head is made.

Having thus described my invention, what 20 I claim as new, and desire to secure by Letters Patent of the United States, is—

1. In a car-coupling, the draw-head, the cranked shafts, the sliding catch, and arrow-head bolt *D*, in combination with the releasing devices consisting of the vertical shaft 25 provided with a lever, *M*, and key *J*, and the chains *N*, extending from said lever to points near the sides of the car, substantially as shown and described.

2. In a car-coupling, the draw-head *A*, the 30 shafts *C*, having cranks *H'* and *h'*, the sliding catch *B*, the key *J*, and an arrow-head bolt, *D*, arranged substantially as shown and described.

In testimony whereof I hereunto affix my 35 signature in presence of two witnesses.

BROOKS BUSH.
